DESIGN FOR A DRESS

Ruthe E. Knapp, New York, N. Y.

Application July 15, 1939, Serial No. 86,034

Term of patent 3½ years

To all whom it may concern:

Be it known that I, Ruthe E. Knapp, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific panel arrangement on the back portion of the dress in combination with the specific buttons down the front of the waist as shown.

I claim:

The ornamental design for a dress, substantially as shown and described.

RUTHE E. KNAPP.
